Primary Examiner — Selina Sikder(74) *Attorney, Agent, or Firm* — Wilson Sonsini Goodrich & Rosati(57) **CLAIM**

The ornamental design for a controller unit housing as shown and described.

DESCRIPTION

FIG. 1 is perspective view of the controller unit housing showing my new design;

FIG. 2 is a right view of the controller unit housing of FIG. 1;

FIG. 3 is a left view of the controller unit housing of FIG. 1;

FIG. 4 is a rear view of the controller unit housing of FIG. 1;

FIG. 5 is a front view of the controller unit housing of FIG. 1;

FIG. 6 is a top view of the controller unit housing of FIG. 1; and,

FIG. 7 is a bottom view of the controller unit housing of FIG. 1.

In the drawings the broken lines depict portions of the controller unit housing that form no part of the claimed design.
